To all whom it may concern:

Be it known that I, JOSEPH K. DAVISON, a citizen of the United States, residing in the city and county of Philadelphia, State of Pennsylvania, have invented and produced a new and original Design for a Badge, of which the following is a specification, reference being had to the accompanying photograph, forming part thereof.

10. The leading features of my design for a badge are, first, a star with a star on each point and a segmental wreath with the segments joining the sides of the points of the main star, and, next, a bar having side bosses with stars thereon.

15. A represents a five-pointed star having a star, *a*, on each point. In the center of the star is the seal *b*, and between the points, and extending from the side of one point to the side of the next point of the main star, are segments *c* of a wreath, leaving the points of the main star and the stars thereon uncovered.

20. A represents a five-pointed star having in the center thereof the seal *b*, with the circum-

scribed border, from which the points *A'* of 25 the star extend. Within the field of the points are stars *a*, and between the points, extending from one to the other thereof, are segments of a wreath, *c*.

I claim—

1. A design for a badge, consisting of a main star with a central seal, stars on the field of the points of said main star, and segments of a wreath between said points, as shown and described. 30
